United States Patent Office

Des. 226,882

Patented May 15, 1973

226,882

SHOE

Alfred Powers, Los Angeles, Calif., assignor to Nippon Rubber U.S.A. Corp., Los Angeles, Calif.

Filed May 17, 1971, Ser. No. 144,380

Term of patent 14 years

Int. Cl. D2—04

U.S. Cl. D2—268

Fig. 1

Fig. 2

Fig. 3

Fig. 4

FIG. 1 is a side elevational view of a shoe showing my new design;

FIG. 2 is a top plan view thereof;

FIG. 3 is an elevational view of the side opposite that shown in FIG. 1; and

FIG. 4 is a bottom plan view.

I claim:

The ornamental design for a shoe, as shown.
